UNITED STATES PATENT OFFICE

2,610,237

ELECTRIC POWER INDICATING SWITCH

Lloyd N. Benner, Brunswick, Maine

Application November 16, 1949, Serial No. 127,744

4 Claims. (Cl. 177—311)

1

This invention relates to an electrical testing device for permanent attachment to a junction box, and in particular to a device for indicating the presence of electrical power at a switch box or breaker cabinet located on the premises of a consumer and connected to the main supply line of the premises. In the event that a lack of current exists at some outlet on the consumer's premises it is desirable to determine quickly whether the trouble results from a defect in the fuses or wiring of the consumer's distribution system or from a failure of power on the main supply line, and thus whether the consumer should report the trouble to his electrician or to the power company. Especially in rural areas it is desirable that the power company be spared long and expensive service trips when the trouble results from a blown fuse which might be replaced locally.

So that such a device for use by a consumer will be reliable it should be rugged in construction and capable of simple operation. Since it is to be produced in great quantities for general installation it should be simple in design, adapted for attachment to standard switch boxes and require a minimum of electrical wiring, and should be sufficiently safe to receive the approval of the underwriters' laboratories.

Objects of the present invention therefore are to provide a reliable testing device, which is durable and capable of mass production and which may be safely and easily attached to standard equipment commonly installed on the premises of a power consumer. A specific object is to provide a testing device which may be easily mounted in the knock-out hole of a standard switch box.

In one aspect the invention involves the combination of a tubular sleeve which contains a pair of electrical contacts held apart by suitable resilient means, a contact closing member adapted to slide within the sleeve to move the contacts between open and closed condition, and a lamp within the sleeve. In one aspect of the invention a distinguishing feature comprises threaded portions of different diameters at the ends of the sleeve, the threaded portions being of proper size for insertion in a knock-out hole of one of two standard diameters. The sleeve may be secured in a knock-out hole and the contacts and lamp connected in series with the terminal of a switch box and the device may be operated to indicate the presence of electrical power at said terminals. In another aspect the sleeve is provided interiorly with

5 a portion of reduced diameter which provides an annular abutment opposed to the inner end of the sliding member and insulating discs are fitted in the sleeve to bear against the abutment and the inner end of the sliding member respectively, the discs being provided with contacts and held apart by a helical spring or other resilient means and capable of being closed on movement of the tubular member to complete a circuit between the energized and grounded terminal of the switch box through a lamp mounted within the tubular sleeve thereby affording a simply constructed device for indicating the presence of electrical power at the terminals.

15 For the purpose of illustration a typical embodiment of the invention is illustrated in the accompanying drawing in which

Fig. 1 is a side elevation of the testing device mounted on a switch box shown partly in section;

20 Fig. 2 is an end view of the device and switch box;

Fig. 3 is a section on line 3—3 of Fig. 2;

25 Fig. 4 is a wiring diagram showing the connection of the testing device to the switch box;

Figs. 5 and 6 are side elevations of modified devices; and

30 Fig. 7 is a sectional view of the device shown in Fig. 6.

The embodiment of the testing devices illustrated in Figs. 1 to 4 includes an outer tubular casing 1 of conducting metal provided at its ends with threaded portions 2 and 3 for mounting the casing in a knock-out hole 4 or 4a in the wall 6 of a switch box 7. As shown in Fig. 3 a tubular sleeve 8 of translucent plastic slides in the bore 9 of the casing 1. A hollow portion 11 of reduced diameter extends outside the casing 1 through an opening 12 in a retaining screw cap 13. The extended portion 11 serves as a push button and as an enclosure for a neon lamp L. Adjacent the smaller threaded end 2 the bore of the casing 1 is reduced in diameter to provide an annular abutment 14 opposed to the inner end 16 of the sleeve 8. Insulating discs or plugs 17 and 18 are held respectively against the abutment 14 and the inner end 16 of the sleeve by a helical spring 19. Preferably positioning discs or protuberances 21 are fixed to the insulating plugs 17 and 18 to space the spring from the contacts 22. Hollow shanked rivets 22 which join the insulating and positioning discs are located centrally on the discs. The heads of the rivets 22 are opposed and act as contacts when brought together by operation of the push button por-

tion 11. The neon lamp L is held in position within the translucent sleeve 8 by a soldered connection of one of the lamp lead wires 23 and the outer hollow rivet 22. The other lamp lead wire 23 is connected to a dropping resistor R from which a lead wire passes through the disc 18 at one side of the disc where it is turned to provide a lamp terminal 20 which makes contact with the spring 19. An extension 24 of the opposite end of the spring passes through the plug 17 and makes contact with the abutment 14 of the casing 1. An insulated wire 26 interconnects the inner rivet 22 with a switch box terminal (Fig. 4).

As shown in Fig. 4 the grounded main power line G is electrically connected to the switch box 7 and the junction box is grounded according to standard practice. The energized or potential carrying power line is connected to an insulated terminal E. A fuse F is interposed between the terminals E and the lines to the local distribution cabinet. When contacts 22 are closed current flows from terminal E through the contacts, through the lamp L and the resistor R to the casing 1, and thence through the walls of the switch box 7 to the grounded terminal G.

According to the embodiment of Figs. 1-3 threaded portions 2 or 3 of sleeve 1 make electrical contact with the walls of the grounded switch box thus eliminating a two-conductor connection between the lamp and the terminals. This design is made feasible by providing threaded portions 2 and 3 with a diameter slightly less than that of two standard sized knock-cut holes 4 and 4a of half inch and three-quarter inch diameters respectively. Thus, the device may be secured in a knock-out hole at either end—at the smaller end 2 by means of a nut 27 (Fig. 1), or at the larger end by means of a nut 28 and the retaining cap 13.

In the modified embodiment shown in Figs. 5 to 7 the stationary insulating plug 17a and the movable plug 18a are provided with telescoping walls 31 and 32 respectively which space the spring 19 away from the contacts 22 carried by the plugs and provide added insulation between the spring and the contacts. A recess 33 is provided in the outer end of the movable plug 18a to receive the dropping resistor R and the leads 23 from the lamp L to the resistor and one contact rivet 22. A lead wire from the resistor passes from recess 33 through plug 18a, and is turned to form a lamp terminal 20 contacted by the outer end of spring 19. The other end of the spring which bears against the stationary plug 17a is expanded so that it makes an electrical contact with the bore 9 of casing 1. The casing 1 may be partially enclosed by the cap 13 having central opening 12 (Figs. 6 and 7) or by a peripheral flange 13a (Fig. 5) turned in during manufacture.

In the embodiment shown in Figs. 5 to 7 the plugs 17a and 18a may be inserted in the casing 1 in the position shown in Fig. 7 or in reversed position, so that the push button 11 extends through the peripheral flange 13a or the cap 13 at the wider end of the casing (Figs. 5 and 7), or through the reduced end of the casing 2 (Fig. 6). Thus the casing may be mounted in the knock-out hole of a switch box to extend from the wall 6 of the switch box (Fig. 5) or so that it is substantially flush with the wall. The location of the push button may be selected by the manufacturer where the peripheral flange 13a of Fig. 5 is employed or by the user where the threaded cap 13 is used. In either case the use of the re-

versible plugs allows a simple variation in assembly affording a construction which is economical to manufacture and easy to use.

It should be understood that the present disclosure is for the purpose of illustration only and that this invention includes all modifications and equivalents which fall within the scope of the appended claims.

I claim:

1. For attachment in a mounting hole of a switch box or the like, an electric power indicating switch comprising a tubular casing carrying mounting means for securing one end of the casing in said hole, an internal abutment forming a restricted opening at one end of the casing, means providing a second internal abutment and restricted opening at the other end of the casing, a pair of blocks slideable in the casing, opposed contacts on said blocks, a spring urging the blocks respectively toward said abutments to hold said contacts apart, plunger means extending into the casing through one of said openings and operable to urge the blocks toward each other until their contacts meet, said plunger means having a light transmitting push button portion of smaller dimension than either opening, lamp means connected to the contact of one block, said blocks being substantially of the same dimension transversely of said bore, whereby said switch may be assembled with said one contact carrying block and lamp selectively disposed adjacent either end opening and with the plunger extending through the selected end opening and said casing may be attached either outside said mounting hole or substantially flush with said hole and with the plunger disposed outside the switch box.

2. For attachment in a mounting hole of a switch box or the like, an electric power indicating switch comprising a tubular casing carrying mounting means for securing one end of the casing in said hole, an internal abutment forming a restricted opening at one end of the casing, means providing a second internal abutment and restricted opening at the other end of the casing, a pair of blocks slideable in the casing, opposed contacts disposed centrally on said blocks, a spring urging the blocks respectively toward said abutments to hold said contacts apart, said spring having a coil of diameter to contact the inside of said casing, plunger means extending into the casing through one of said openings and operable to urge the blocks toward each other until their contacts meet, said plunger means having a light transmitting push button portion of smaller dimension than either opening, lamp means connected to the contact of one block, a conductor connected at one end to said lamp and having its other end disposed between said spring and said one block, said blocks being substantially of the same dimension transversely of the inside of said casing and having mutually telescoping wall members around said contacts, whereby said switch may be assembled with said one contact carrying block and lamp selectively disposed adjacent either end opening and with said push button portion extending through the selected end opening and said casing may be attached either outside said mounting hole or substantially flush with said hole and with the plunger disposed outside the switch box, said telescoping wall members insulating the contacts from the spring.

3. For attachment in a mounting hole of a

switch box or the like, an electric power indicating switch comprising a tubular casing carrying mounting means for securing one end of the casing in said hole, lamp means within the casing, a pair of spring-opened blocks carrying contacts for completing a circuit to the lamp, a plunger slidable in the casing and operable to close said contacts, said casing having a shoulder forming an internal abutment at said one end and means forming an internal abutment at the other end of the casing, said abutments confining said blocks and plunger within the casing, and said plunger having a light transmitting push button portion dimensioned to extend outside the casing past either of said abutments so that the switch may be assembled with the plunger extending past either one of the abutments and with the contact blocks against the other abutment, whereby the casing may be mounted either

outside said switch box mounting hole or substantially flush with said hole and with the plunger extending outside the switch box.

4. The switch according to claim 1 characterized in that said spring is in helical form around said contacts, and said blocks carry mutually telescoping tubular portions disposed between said spring and said contacts to insulate said contacts from said spring.
